UNITED STATES PATENT OFFICE

130,739

DESIGN FOR A THERMOMETER CASING OR SIMILAR ARTICLE

Eric A. Bandoly, St. Louis, Mo., assignor to American Thermometer Company, St. Louis, Mo., a corporation of Delaware

Application October 10, 1941, Serial No. 103,703

Term of patent 14 years

To all whom it may concern:

Be it known that I, Eric A. Bandoly, a citizen of the United States and a resident of the city of St. Louis, in the county of St. Louis and State of Missouri, have invented a new, original, and ornamental Design for a Thermometer Casing or Similar Article, of which the following is a specification, reference being had to the accompanying drawing, forming part thereof.

Fig. 1 is a front elevation of a thermometer casing or similar article showing my new design;

Fig. 2 is a plan view; and

Fig. 3 is a side elevation.

I claim:

The ornamental design for a thermometer casing or similar article, as shown.

E. A. BANDOLY.
